UNITED STATES PATENT OFFICE

162,872

PIPE RACK

Harold C. Pierce, Leominster, Mass.

Substituted for design application Serial No. 140,513, July 25, 1947. This application March 22, 1950, Serial No. 8,704

Term of patent 7 years

(Cl. D85—8)

To all whom it may concern:

Be it known that Harold C. Pierce, a citizen of the United States, residing at Leominster, in the county of Worcester and State of Massachusetts, has invented a new, original, and ornamental Design for Pipe Rack, of which the following is a specification, reference being had to the accompanying drawing, forming part thereof.

Fig. 1 is a side elevational view of a pipe rack, showing my new design;

Fig. 2 is a top plan view thereof.

This is a refiled application for my former case on Pipe Rack, filed July 25, 1947, Serial No. D. 140,513, which is now abandoned.

I claim:

The ornamental design for a pipe rack, as shown.

HAROLD C. PIERCE.
